[57] CLAIM

The ornamental design for a “lighting fixture louver”, as shown and described.

DESCRIPTION

FIG. 1 is a three dimensional perspective view of a “lighting fixture louver” employing Applicants’ new design.

FIG. 2 is a top plan view of the “lighting fixture louver” depicted in FIG. 1.

FIG. 3 is a front elevational view of the “lighting fixture louver” depicted in FIG. 1.

FIG. 4 is a bottom plan view of the “lighting fixture louver” depicted in FIG. 1.

FIG. 5 is a right side elevational view of the “lighting fixture louver” depicted in FIG. 4, the left elevational view being a mirror image FIG. 5.

FIG. 6 is a cross sectional view of the “lighting fixture louver” depicted in FIG. 2 and taken along lines 6-6.
